JAMES B. FURBER, OF RAHWAY, NEW JERSEY.

AQUATIC TOY.

1,323,876.

Specification of Letters Patent.

Patented Dec. 2, 1919.

Application filed July 15, 1918. Serial No. 244,917.

To all whom it may concern:

Be it known that I, WILLIAM EARLE LAWSON, a citizen of the United States, and a resident of Rahway, in the county of Union 5 and State of New Jersey, have invented a new and Improved Aquatic Toy, of which the following is a full, clear, and exact description.

The object of the invention is to provide 10 a new and improved aquatic toy more especially designed to simulate a marine vessel such as a submarine, and arranged to be submerged in a body of water, to be moved along in the body of water and 15 caused to rise to the surface and travel along the same at the will of the operator. Another object is to provide movable members such as flags, images of officers, sailors and other persons, ordnance and the like, 20 held in inactive folded position when the vessel is submerged and moved into active position on the vessel rising to the surface. Another object is to automatically fire toy 25 torpedoes, toy guns or similar weapons.

With these and other objects in view, the 30 invention consists of certain novel features of construction as hereinafter shown and described and then specifically pointed out in the claims.

A practical embodiment of the invention 35 is represented in the accompanying drawings forming a part of this specification, in which similar characters of reference indicate corresponding parts in all the views.

Figure 1 is a longitudinal central section 40 of the aquatic toy in the form of a submarine, the section being on the line 1—1 of Fig. 3, and the parts shown in position when the vessel is submerged;

Fig. 2 is a similar view of the same with 45 the vessel in floating position on the surface of the water;

Fig. 3 is a reduced plan view of the same;

Fig. 4 is a longitudinal central section 50 of a modified form of the aquatic toy;

Fig. 5 is a similar view of another modified form of the aquatic toy; and

Fig. 6 is a similar view of another modified form of the aquatic toy.

The aquatic vessel is preferably in the 55 form of a toy submarine having a hull 10 made of sheet-metal or similar material and covered by a deck 11 of wood or other light, floatable material and from which rises a post 12 imitating a periscope. The hull

10 is adapted to be filled with water, preferably derived from a body of water on which the vessel is used, and for this purpose the hull 10 is provided at the bow and stern with openings 13 forming passage- 60 ways for the water to flow into the hull or out of the same.

Within the hull 10 and preferably amidship thereof is arranged a chamber 15 closed at the sides and top and open at the bottom 65 a short distance above the bottom of the hull 10. The chamber 15 preferably extends with its upper portion above the deck 11 thus simulating a conning tower, and into the upper end opens an air supply pipe 70 16 extending down through the chamber 15 and out of the same and forwardly, finally passing through the bow to the outside of the hull 10. To the outer end of this pipe 16 is secured a rubber tube 17 terminating 75 in an air pressure bulb 18 which when pressed forces air into the upper end of the chamber 15 with a view to force some of the water out through the openings 13, as hereinafter more fully explained. The parts 80 so far described are common to the various forms illustrated in Figs. 1 to 6, and of which the latter figure shows the aquatic toy in its simplest form.

It will be noticed that in the simple form 85 shown in Fig. 6 the hull 10 can be readily filled with water by holding the vessel upside down and pushing it under the surface of a body of water contained in a tub, lake, stream or other waterway. When the hull 90 10 has filled with water it readily sinks in the body of water and eventually rights itself owing to the deck 11 forming a large and exceedingly buoyant member. Now while the vessel is submerged in the body of 95 water it can be readily dragged along under water by the operator pulling on the tube 11. When it is desired to have the vessel rise to the surface of the body of water, it is only necessary for the operator to squeeze 100 the bulb 18 thus forcing air by way of the flexible tube 17 and the pipe 16 into the upper end of the chamber 15 whereby some of the water is displaced therein and forced out of the hull 10 by way of the openings 105 13. By this operation the buoyancy of the vessel causes the latter to rise to the surface of the body of water and the vessel can now be drawn along in this position by the operator exerting a corresponding pull on 110

the flexible tube 17. When it is desired to again submerge the vessel it is only necessary for the operator to release the pressure on the bulb 18 so that the bulb again becomes inflated by the return of the air from the chamber 15 on the refilling of the hull 10 and chamber 15 by the water entering the openings 13. The above described operation can then be repeated at the will of the operator, that is, the vessel can be moved along either when submerged or when afloat, and the vessel can be caused to rise or be submerged on the operator pressing and releasing the bulb 18, as above explained.

15 In the form shown in Fig. 1, the chamber 15 is provided with a float or piston 20 rising or falling with the water in the chamber 15. The float 20 controls movable parts, such, for instance, as a projectile 25 arranged in a torpedo tube 26, or a toy gun 30 containing a projectile 31, or a flag 35 having its flagstaff 36 attached to the base 37 of the gun 30 to be moved up and down with the latter. A torpedo tube 26 is fixed in the deck 11 and extends forwardly, and the projectile 25 is pressed on by a spring 40 held in the rear end of the tube 26. The projectile 25 is provided with an annular groove 41 engaged by a pin 42 on a locking and releasing lever 43 fulcrumed at 44 on the under side of the deck 11 and pressed on by a spring 45 to normally hold the pin 42 in engagement with the groove 41 to lock the projectile 25 in position in the tube 26 and 30 against the tension of the spring 40. The lever 43 extends through a slot 46 formed in one side of the chamber 15 to be with its free end in the path of the float 20. When the vessel is caused to rise, as previously explained, by the downward movement of the float 20 displacing some of the water in the hull 10 then the float 20 comes in contact with the lever 43 and swings the same downward against the tension of the spring 45. 45 This downward movement of the lever 43 causes the pin 42 to disengage the groove 41 thus releasing the projectile 25 which is now propelled out of the tube 26 by the action of the spring 40.

50 The base 37 of the gun 30 is mounted to slide up and down in a suitable guideway 50 arranged on the deck 11 so that the gun 30 is normally received in a recess 51 formed in the top of the deck 11, as plainly indicated in Fig. 1. The bottom of the base 37 is provided with an elongated slot 52 into which projects a pin 53 held on one end of a lever 54 fulcrumed at 55 on the lower end of the chamber 15. The other end of the lever 54 is provided with a pin 56 engaging an elongated slot 57 formed on the under side of the float 20 so that when the latter moves downward, as previously explained then a swinging motion is given to the lever 54 whereby the latter raises the gun 30

above the deck, as indicated in Fig. 2. The projectile 31 is pressed on by a spring 60 arranged in the rear end of the gun 30, and the projectile is provided with an annular groove 61 engaged by a pin 62 formed on a releasing lever 63 fulcrumed on the top of the gun 30. The releasing lever 63 is adapted to engage an arm 65 held on the upper end of the chamber 15 to impart a swinging motion to this lever 63 at the time the gun 30 moves into uppermost position whereby the pin 62 moves out of engagement with the groove 61 thus releasing the projectile 31. The latter is now fired out of the gun 30 by the action of the spring 60 which is held under tension by the projectile 31 when the latter is in locked position within the gun 30.

The flag 35 is normally concealed within the hull and when the base 37 of the gun 30 is raised as above explained then the flag is moved upward through a slot 70 formed in the deck 11 at the stern thereof thus displaying the flag at the time the vessel is afloat on the surface of the water. It is understood that when the float 20 rises within the chamber 15 the gun 30 is returned to lowermost concealed position by the action of the lever 54 connecting the base 37 of the gun with the float 20. It is further understood that prior to the next submerging of the vessel the projectiles 25 and 31 can be replaced in the tubes 26 and 30 if it is desired to do so. Instead of the float 20 other means may be employed for imparting movement to the disappearing gun and other devices; for instance, as shown in Fig. 4, the disappearing toy gun 80 has its base 81 attached to the movable member 82 of a bellows 83 having its member 84 fixed in the hull 10 and connected by a pipe 85 with the pipe 16. Normally the bellows 83 are deflated and the gun 80 is received in a recess 85 formed in the deck 11 of the vessel. When the air pressure is forced through the pipe 16, as previously explained, and a portion of this air passes by way of the pipe 85 into the bellows 83 to extend the latter then the gun 80 is moved upward into display position, as shown in Fig. 4. The movable member 82 of the bellows 83 also carries the staff 86 of a flag 87 normally arranged within the hull 10 and adapted to pass into display position through an opening 88 formed in the deck 11. The movable member 82 of the bellows may also be provided with an upwardly extending base 90 mounted to slide in a guideway 91 formed in the deck 11 and supporting a miniature representation 92 of a gunner adjacent the breech end of the gun 80. It is understood that this figure moves into disappearing position on the deflating of the bellows 83.

In the modified form shown in Fig. 5, use is made of hollow inflatable rubber figures

100, 101, 102, of which the inflatable rubber figure 100 simulates a gun mounted on a hollow base 103 attached to or in communication with a pipe 104 connected with the 5 pipe 16. When the bulb 18 is pressed and air is forced through the pipe 16 then a portion of this air passes into the base 103 and the gun 100 thus moving the gun from the closely folded position in the recess 105 in 10 the deck 11 into extended display position, as plainly indicated in Fig. 5. The figure 101 is in the form of a gunner normally held deflated in a recess 106 formed in the deck 11 and when inflated by air pressure 15 from the pipe 104 moves into display position at the breech end of the gun 100. The terminal of the pipe 104 connects with the rubber staff 102 of a flag 107 normally folded in a recess 108 on the top of the deck 11. 20 When this staff 102 is inflated by air pressure from the pipe 104 the flag 107 is raised from its folded position into display position, as indicated in Fig. 5. It is understood that normally the figures 100, 101 and 102 25 are in folded deflated position on the deck 11, but when air pressure is forced into the chamber 15 a portion of this pressure passes into the hollow rubber figures to inflate the same and thereby move the figures into 30 display position.

From the foregoing it will be seen that the vessel can be readily submerged, raised, or moved about while under the water or floating on the surface thereof on the 35 operation simply pressing and releasing the bulb, and the various devices, such as the various movable figures, mounted on the vessel can be readily moved into active or display position on raising the vessel, and moved into 40 inactive or folded position on submerging the vessel.

Although I have shown some imitations of devices now generally used on submarines I do not limit myself to the devices shown 45 and described as the same can be readily varied and differently located without deviating from the spirit of my invention.

Having thus described my invention, I 50 claim as new and desire to secure by Letters Patent:—

1. An aquatic toy comprising a buoyant aquatic vessel simulating a submarine and having an opening for the passage of water into the said vessel to sink it in a body of 55 water, the said opening also forming an exit for the water to pass out of the vessel to allow the latter to rise in the body of water, an air pressure displacement chamber in the said vessel and closed at the sides and top 60 and open at the bottom adjacent the bottom of the said vessel, and air pressure supplying means under the control of an operator and connected with the upper end of the said displacement chamber to force the water 65 out of the same into the hull and out of the

said opening to cause the submarine to rise to the surface of the said body of water.

2. An aquatic toy, comprising a buoyant aquatic vessel simulating a submarine and having an opening for the passage of water 70 into the said vessel to sink it in a body of water, the said opening also forming an exit for the water to pass out of the vessel to allow the latter to rise in the body of water, an air pressure displacement chamber in the said vessel and closed at the sides and top 75 and open at the bottom adjacent the bottom of the said vessel, a pipe extending from the upper portion of the said chamber to the bow of the vessel, a flexible tube connected with the forward end of the said pipe, and a bulb connected with the said tube to force air into the said chamber to displace the water therein, the said flexible tube and bulb forming a means for drawing the submarine 80 when submerged or afloat on the said body of water.

3. An aquatic toy, comprising a buoyant aquatic vessel simulating a submarine and having an opening for the passage of water 85 into the said vessel to sink it in a body of water, the said opening also forming an exit for the water to pass out of the vessel to allow the latter to rise in the body of water, an air pressure displacement chamber in the 90 said vessel and closed at the sides and top and open at the bottom adjacent the bottom of the said vessel, air pressure supplying means under the control of an operator and connected with the upper end of the said displacement chamber to force the water 95 out of the same into the hull and out of the said opening to cause the submarine to rise to the surface of the said body of water, and miniature devices simulating active means 100 on board of a submarine and mounted on the said vessel and normally lowered, the said devices being adapted to move into extended position on the submarine rising to the surface of the said body of water.

4. An aquatic toy, comprising a buoyant aquatic vessel simulating a submarine and having an opening for the passage of water into the said vessel to sink it in a body of water, the said opening also forming an exit for the water to pass out of the vessel to allow the latter to rise in the body of water, an air pressure displacement chamber in the said vessel and closed at the sides and top 115 and open at the bottom adjacent the bottom of the said vessel, a pipe extending from the upper portion of the said chamber to the bow of the vessel, a tube connected with the forward end of the said pipe, a bulb connected with the said tube to force air into the said chamber to displace the water therein, the said tube and bulb forming a means 120 for drawing the submarine along when submerged or afloat on the said body of water, miniature devices simulating active means 125 130

on board of a submarine normally held lowered in the said hull, and means whereby the said devices will be moved into extended position when the submarine rises to the 5 surface of the water.

5. An aquatic toy, comprising a buoyant aquatic vessel simulating a submarine and having an opening for the passage of water into the said vessel to sink it in a body of 10 water, the said opening also forming an exit for the water to pass out of the vessel to allow the latter to rise in the body of water, an air pressure displacement chamber in the said vessel and closed at the sides and top 15 and open at the bottom adjacent the bottom of the said vessel, air pressure supplying means under the control of an operator and connected with the upper end of the said displacement chamber to force the water 20 out of the same into the hull and out of the said opening to cause the submarine to rise to the surface of the said body of water, the said air pressure means including a float rising and falling in the said air pressure 25 chamber, and toy warfare devices mounted on the said vessel and controlled by the said float.

6. An aquatic toy, comprising a buoyant aquatic vessel simulating a submarine and 30 having an opening for the passage of the water into the said vessel to sink it in a body of water, the said opening also forming an exit for the water to pass out of the vessel to allow the latter to rise in the body 35 of water, an air pressure displacement chamber in the said vessel and closed at the sides and top and open at the bottom adjacent the bottom of the said vessel, air pressure supplying means under the control of an 40 operator and connected with the upper end of the said displacement chamber to force the water out of the same into the hull and out of the said opening to cause the submarine to rise to the surface of the said body 45 of water, the said air pressure means including a float movable up and down in the said air pressure chamber, a toy torpedo tube mounted on the said vessel, a spring pressed projectile in the said tube, and locking and 50 releasing means mounted in the said vessel and controlled by the said float, the locking and releasing means engaging the said projectile and holding the same locked against the tension of its spring, and the said locking and releasing means releasing the said projectile on the vessel rising to the surface 55 of the body of water.

7. An aquatic toy, comprising a buoyant aquatic vessel simulating a submarine and 60 having an opening for the passage of water into the said vessel to sink it in a body of water, the said opening also forming an exit for the water to pass out of the vessel to allow the latter to rise in the body of water, 65 an air pressure displacement chamber in the

said vessel and closed at the sides and top and open at the bottom adjacent the bottom of the said vessel, air pressure supplying means under the control of an operator and connected with the upper end of the said displacement chamber to force the water out of the same into the hull and out of the said opening to cause the submarine to rise to the surface of the said body of water, the said air pressure means including a float 70 movable up and down in the said air pressure chamber, a miniature disappearing gun mounted on the said vessel, and means connecting the said gun with the said float to hold the gun in disappearing position while 75 the vessel is submerged and to move the gun into raised firing position on the vessel rising to the surface of the water.

8. An aquatic toy, comprising a buoyant aquatic vessel simulating a submarine and 80 having an opening for the passage of water into the said vessel to sink it in a body of water, the said opening also forming an exit for the water to pass out of the vessel to allow the latter to rise in the body of water, an air pressure displacement chamber in the said vessel closed at the sides and top and open at the bottom adjacent the bottom of the said vessel, and air pressure supplying means under the control of an operator and connected with the upper end of the said displacement chamber to force the water out of the same into the hull and out of the said opening to cause the submarine to rise to the surface of the said body of water, the 85 said air pressure means including a float movable up and down in the said air pressure chamber, a miniature disappearing gun mounted on the said vessel, means connecting the said gun with the said float to hold the gun in disappearing position while the vessel is submerged and to move the gun into raised firing position on the vessel rising to the surface of the water, a projectile in the 90 said gun, a spring pressing the said projectile, and a locking and releasing means adapted to lock the said projectile against the tension of the said spring while the vessel is submerged and adapted to release the 95 said projectile on the vessel rising to the 100 surface of the water.

9. In an aquatic toy of the character described, a vessel having a chamber, a float in the chamber, means for forcing air into the chamber above the float, miniature devices 105 simulating active means on board of the vessel, and means for operating the devices from the float.

10. In an aquatic toy of the character described, a vessel having a chamber, a float in 110 the chamber, means for forcing air into the chamber above the float, a miniature disappearing gun mounted in the vessel, and means whereby the gun will be elevated when the float is forced down.

11. In an aquatic toy of the character described, a vessel having a chamber, a float in the chamber, means for forcing air into the chamber above the float, a disappearing gun mounted in the vessel, and an angular lever connected with the bottom of the float and with the base of the gun.
12. In an aquatic toy of the character described, a vessel having openings for the admission of water into the same, a chamber closed at its top and extending above
- 5 the vessel, the lower end of the chamber being in communication with the interior of the vessel, a float in the chamber, devices simulating active means on the vessel, and 15 means connecting the devices with the float, and means for forcing air into the vessel above the float, whereby the water will be forced out of the vessel and the devices operated.

WILLIAM EARLE LAWSON.
